UNITED STATES PATENT OFFICE.

FREDERICK W. LEWIS, OF PROVIDENCE, RHODE ISLAND, ASSIGNOR TO CHAPIN & HOLLISTER CO., OF PROVIDENCE, RHODE ISLAND, A CORPORATION OF RHODE ISLAND.

METHOD OF FORMING A BUCKLE-BODY.

1,395,124.

Specification of Letters Patent. Patented Oct. 25, 1921.

Application filed August 9, 1920. Serial No. 402,324.

To all whom it may concern:

Be it known that I, FREDERICK W. LEWIS, a citizen of the United States, residing at Providence, in the county of Providence and 5 State of Rhode Island, have invented certain new and useful Improvements in Methods of Forming a Buckle-Body, of which the following is a specification.

This invention relates to an improved 10 method of forming a one-piece belt buckle having longitudinally curved sides and rearwardly inturned flanges with inturned edges; and the object of this invention is to provide simple and effective means for carrying out my improved method whereby the 15 side edges of this buckle body may be first turned up and then folded over a collapsible arbor which is previously expanded within the body and after the edges have been 20 turned thereover the arbor may be collapsed or reduced in size and then withdrawn from this body.

The nature and advantages of the invention will be better understood when the following 25 detail description is taken in connection with the accompanying drawings:

In the drawings forming part of this specification, like numerals of reference indicate similar parts in the several views and 30 wherein:—

Figure 1 is a perspective view showing my improved buckle body in finished form.

Fig. 2 is a top view illustrating the collapsible arbor as positioned in the buckle body which has been swaged into finished 35 form.

Fig. 3 is an end view of the buckle body showing the same after the side edges have been turned up and the swaging tools in 40 position to fold these side edges inwardly over the collapsible arbor which is shown in section therein.

Fig. 4 shows the tools as having been brought together and the side edges of the 45 buckle folded over the face of the collapsible arbor.

Fig. 5 is a side elevation sectioned on line 5—5 of Fig. 4.

Fig. 6 is a perspective view showing two 50 of the members of the collapsible arbor from which the third member has been withdrawn.

The essential feature of my improved buckle is that the same is made complete of 55 one piece of metal without the use of solder

which would be a comparatively simple operation if it were not for the fact that the side edges of the buckle were curved longitudinally and also that these edges were bent or set inwardly so as to overlap the edges of 60 the arbor over which these edges are finally formed, by which construction it is found necessary to provide special means for permitting the withdrawal of the arbor after the metal has been folded thereover; and the 65 following is a detailed description of one method by which this result may be accomplished:—

The buckle body is first blanked out of sheet stock into the proper shape having a 70 body portion with side edges 10 rounded lengthwise thereof. These side edges are then drawn up by suitable drawing tools (not shown) and the front plate 11 is at the same time swaged to produce its crowning or oval contour both longitudinally and transversely, as best illustrated in Figs. 4 and 5.

In producing a fine quality of goods, I next stamp this body by a drop press operation or other means, to produce a suitable finish on its face and side edges. I then trim the edges to the exact shape desired after which I place a collapsible arbor 12 into the body, which arbor comprises a pair of side 80 or edge fingers 13 which are made the exact shape in which the edges of the body portion are to be formed. The outer ends 14 of these fingers are connected together by means of the bar 15 to which one of these fingers is 85 shown as being rigidly attached by pins 16 while the other is pivotally mounted to this bar to swing thereon, by the pivot pin 17. An expanding middle member 18 of this arbor is fitted to be forced in between these side 90 edge forming members, to expand the same and hold them in that position during the 95 next swaging operation.

With this collapsible arbor now in position in the body member I place the same onto 100 the bed 19 of the lower swaging die and then by forcing downwardly the upper swaging die 20, the edge flanges 21 and guide lips 22 on these side flanges, are turned inwardly and so folded over the upper face of the collapsible die into the position best illustrated in Fig. 2.

At the same time I preferably incline the side flanges 10 inwardly over the side edges of the collapsible arbor, forming the body 110

into somewhat of a dovetailed shape in cross section.

After this last swaging operation the buckle body is removed from the swaging tools and the middle member 18 of the collapsible arbor is withdrawn, permitting the two side members thereof to swing inwardly on their connecting member 15 thus permitting these members to also be withdrawn from the body of the buckle leaving it in a finished condition.

A buckle having side edges of this rounding contour and also having inwardly-extending side walls cannot be formed all of one integral piece without the use of an arbor which is adapted to be subsequently collapsed in order that it may be removed therefrom.

I do not wish to be restricted to the forming of the inturned lips 21 and fingers 22 on the side rounding edges of this buckle as the side edges 10 of such a buckle having inwardly inclined flanges even without these lips also require the use of a collapsible arbor in its construction.

It is found to be of advantage however in buckles of this class to have such guiding edges and lips, as these lips and fingers or their equivalents are essential in guiding the belt therethrough.

Having thus described one illustrative embodiment of my invention and the best mode known to me for carrying out my method, I desire it to be understood that although specific terms are employed, they are used in a generic and descriptive sense and not for the purpose of limitation, the scope of the invention being defined and limited only by the terms of the appended claims.

I claim:

1. An improved method of forming a one-piece buckle body having longitudinally curved side edges and rearwardly turned edge flanges, which consists in cutting the blank from sheet stock, drawing up the side edges thereof, turning inwardly the side edges of the body over an arbor, and finally withdrawing the arbor.

2. An improved method of forming a one-piece buckle body having longitudinally curved side edges and an inturned edge flange, which consists in cutting the blank from sheet stock, drawing up the side edges thereof, trimming the edges, placing an arbor in the body to fit the same, swaging

inwardly the side edges of said body over said arbor, and finally withdrawing the arbor.

3. A collapsible arbor about which a buckle body may be formed comprising a pair of co-extending elongated forming fingers over which material to be shaped is laid transversely across the fingers, said fingers being connected together at one of their opposite ends, one of said fingers being pivotally adjustable relative to the other, and a filler to be inserted between said fingers to form a section of the shaping surface of the arbor and to maintain said fingers in adjustable position against collapsing during the shaping operation.

4. A collapsible arbor of the character described comprising a pair of substantially parallel members over which material to be formed is shaped, a transverse bar connecting said members at one of their ends, one of said members being adjustable on the bar, and means for holding said members in adjusted position on the bar.

5. In a buckle-body forming device, an arbor about which the buckle-body may be formed including a pair of co-extending fingers around which the material to be formed is laid transversely across the fingers, said fingers being connected together and being adjustable relative to each other, an anvil on which said arbor is placed, a swaging die movable relative to the anvil and co-operating therewith, whereby the material on the arbor is shaped.

6. In a buckle-body forming device, an arbor about which the buckle-body may be formed including a pair of co-extending fingers around which the material to be formed is laid transversely across the fingers, said fingers being connected and being adjustable relative to each other, the side edges of said fingers being chamfered, a filler strip to be inserted between the fingers for forming a section of the shaping surface of said fingers and for maintaining the fingers in adjusted position during the shaping operation, an anvil on which said arbor is laid, and a die-head movable relative to the anvil and co-operating therewith, said die-head being adapted to turn and press portions of the buckle-body about the arbor.

In testimony whereof I affix my signature.

FREDERICK W. LEWIS.
